UNITED STATES PATENT OFFICE.

FRANK A. MAGEE, OF WENHAM, MASSACHUSETTS, ASSIGNOR TO THE
MAGEE FURNACE COMPANY, OF BOSTON, MASSACHUSETTS.

HEATING-FURNACE.

SPECIFICATION forming part of Letters Patent No. 625,577, dated May 23, 1899.

Application filed August 15, 1896. Serial No. 602,907. (No model.)

To all whom it may concern:

Be it known that I, FRANK A. MAGEE, a citizen of the United States, residing at Wenham, in the county of Essex and State of Massachusetts, have invented a new and useful Improvement in Heating-Furnaces, of which the following is a full, clear, and exact description, reference being had to the accompanying drawings, forming a part of this specification, in explaining its nature.

The invention relates especially to that class of heating-furnaces known as "gas-burning." Such furnaces assist combustion by the introduction of air into the upper part of the fire-pot or lower part of the combustion-chamber and generate a higher heat than the ordinary type of heating-furnace. The amount of heat so generated in these furnaces is so great as to rapidly burn out the wall of the furnace close to the surface of the fire; and my invention consists in a gas-ring preferably forming a part of the wall of the fire-pot and the inner surface or section of which acts to protect the wall of the ring and the furnace and is also readily removable without taking the furnace apart.

Referring to the drawings, Figure 1 is a view in elevation of a portion of the exterior and a portion of the interior of a heating-furnace equipped with my invention. Fig. 2 is a view in horizontal section thereof upon the dotted line $\alpha\alpha$ of Fig. 1. Fig. 3 is a view in vertical section of the gas-ring of the fire-pot.

The furnace, with the exception of the fire-pot, may have any desired construction. The fire-pot has two sections, the lower of which is of ordinary form. The upper section is formed by a gas-ring comprising an outer wall and a removable protecting inner wall.

A represents the lower section of the fire-pot, B the wall of the combustion-chamber, and C the gas-ring part of the fire-pot. I have represented it in the drawings as having an outer cast-iron wall or shell C', arranged to form a section of the outer wall of the furnace fire-pot and shaped to form a continuous air-passage. It is also shown as made separate or apart from the lower section of the fire-pot wall and from the wall to the combustion-chamber; but I would say that it may be made integral with either or with

both. It is preferably cylindrical in shape, and when made as a separate piece it preferably has about its lower edge a downwardly-extending section or lip c, which enters the recess or cup c' in the upper edge of the lower section of the fire-pot wall. It also then has about its upper edge a recess or cup c'', which receives a downwardly-extending section or lip c''' of the dome or wall of the combustion-chamber. It is covered and lined upon its inner face by the removable section C'', which preferably is made of a number of separate parts and which may be of fire-brick or cast-iron and which are so shaped as to cover the entire inner surface of the section C', being that part of the section of the fire-pot and combustion-chamber which is subjected to the quickest deterioration and wear because of the action of the fire and great heat thereon. This sectional protective gas-ring may be applied to the section C' of the fire-pot wall in any desired way, and I have represented in the drawings as one way of so applying the ring the fashioning or shaping of the outer section C', whereby it is provided with a lower inner face c⁴, an upper inner face c⁵, a lower rest c⁶, and an upper recess c⁷ below the inner face, and which faces, rest, and recess are arranged to receive and hold the parts c⁸ of the said inner section C''. Each of these parts c⁸ is shaped upon its back at c⁹ c¹⁰ to fit the said faces c⁵ c⁴ of the section C', and each has the upper extension c¹¹, which enters the recess c⁷, and the lower extension c¹², which extends upon the rest c⁶. The face c⁴ and rest c⁶ are within the line of the face c⁵, so that the various parts c⁸ of the said inner section C'' are caused to be held in a position inclined from their lower edge outward. (See Figs. 1 and 2.) The vertical edges of the various parts c⁸ are shaped to form a continuous ring, and thus serve to hold the various members against the section C' and secured to each other. I would not be understood, however, as limiting myself to this particular way of applying the said parts c⁸ of the said ring to the said fire-pot section or wall C'. The parts c⁸ of the inner section may be of fire-brick, as represented in Fig. 1, or they may be of cast-iron or other metal, as shown in Fig. 3.

The air-passage D, formed by the inner section C² and the outer section, is preferably continuous about the furnace at the upper edge of the fire-pot wall, and it is connected with the combustion-chamber or the upper part of the fire-pot by inlets d, which extend through the inner section. These inlets may be inclined downwardly, as represented in Fig. 1, or they may be horizontal, as shown in Fig. 3, or have any other direction, and they may be of any desired shape in cross-section. Inlets may also be arranged between the ends of the parts c⁸, as represented in Fig. 3, and when the said parts are made of metal, as shown in Fig. 3, it is desirable that each have lips or flanges e cast thereon to project from one edge and lap upon the inner surface of the next section in order to better hold them in place when they are first applied to the furnace. This is because the parts when made of metal expand by use to such an extent as to make it necessary to provide quite wide spaces at the joints before they have been subjected to heat, and until they have been so expanded there is a chance of their being jostled out of place because of this loose fitting.

Air may be fed or supplied to the air-passage D in any desired way. I have represented as one way the use of one or more inlets F. In Fig. 2 two are shown below the door to the combustion-chamber, and they are formed by hollow interior-threaded bosses f' f', with which short threaded pipe-sections f² f³ screw. These pipe-sections extend through holes in the plate f⁴, to which they are attached by coupling-nuts and form a communication between the chamber f⁵ and the air-passage D, the said chamber f⁵, being formed by a box consisting of the said plate f⁴ and an outer plate f⁶, in which are air-inlets f⁷, adapted to be closed or varied as to size by a sliding damper f⁸. It will be understood that in use the air for better combustion of the fuel or of the gases, is drawn into the passage D and through the distributing-inlets d to the fire.

It will be observed that the removal of a worn or burned out gas-ring section C² and the substitution of a new one to take the place of the old may be accomplished without taking the furnace apart or disturbing the fire-pot or dome. It will also be seen that the removable sections, while they form the inner wall of the air-chamber D, also serve to completely protect that section of the fire-pot from the fire and make it possible to always maintain such section in as good or better condition as any other part of the fire-pot or combustion-chamber wall.

Having thus fully described my invention, I claim and desire to secure by Letters Patent of the United States—

1. The combination in a heating stove or furnace of the section A of the fire-pot wall, 65 the wall B of the combustion-chamber, the independent wall-section C' connected with the fire-pot wall and combustion-chamber wall, having the inner faces c⁴, c⁵, the rest c⁶ and the recess c⁷, with the removable protecting-section C² formed of the parts c⁸ having the faces c⁹, c¹⁰ and the extensions c¹¹, c¹², substantially as described.

2. The combination in a heating stove or furnace of the section A of the fire-pot wall, 75 the wall B of the combustion-chamber, the gas-ring C having the air-passage D and the removable inner section C², the air-chamber f⁵, the sliding damper f⁸ and the pipes f², f³, as and for the purposes described. 80

3. In a heating stove or furnace the combination of the fire-pot wall A, the combustion-chamber wall B and an intermediate wall-section C' curved or shaped to provide upon its inner side a chamber or cavity 85 enclosed upon its top and bottom and outer side and having above and below said chamber or cavity faces or rests with a lining or cover of removable sections of fire bricks or plates having their inner surfaces shaped to bear 90 against said faces and be supported by said rests and completing the said chamber, the said removable sections providing passages from said chamber to the combustion-chamber, and being removable through the doorway to the combustion-chamber without disturbing the fire-pot wall or the wall to the combustion-chamber. 95

4. The combination in a heating stove or furnace of the fire-pot wall A, the combustion-chamber wall B and an independent intermediate gas-ring section comprising the casting C' in the form of a plate outwardly bowed or extended, having at its upper and lower edge sections of joints for connecting 100 it with the fire-pot wall and the combustion-chamber wall, and also having faces and rests upon its inner side near its top and bottom, and removable sectional fire bricks or plates which are shaped upon their back sides to 105 coöperate with said faces and rests as a means for supporting them in position, and passages extending through said plates or rests from the chamber D, which chamber is formed by the said casting C' and said plates or rests. 110

FRANK A. MAGEE.
